[57] CLAIM

The ornamental design for a spiral vaso-occlusive coil, as shown and described.

DESCRIPTION

FIG. 1 is a perspective view of a first embodiment of the spiral vaso-occlusion coil embodying my new design; FIG. 2 is a top plan view thereof; FIG. 3 is a right side elevational view thereof; FIG. 4 is a left side elevational view thereof; FIG. 5 is a front elevational view thereof; FIG. 6 is a rear elevational view thereof; FIG. 7 is a bottom plan view thereof; FIG. 8 is a perspective view of a second embodiment of FIG. 1, the only difference from the first embodiment being the arrangement of fibers; and, FIG. 9 is a perspective view of a third embodiment of FIG. 1, the only difference from the first two embodiments being the arrangement of fibers.
